UNITED STATES PATENT OFFICE

WALTER H. FREYGANG, OF WEEHAWKEN, NEW JERSEY, ASSIGNOR TO WALTER KIDDE & COMPANY, INC., OF NEW YORK, N. Y., A CORPORATION OF NEW YORK

MANUAL RELEASE FOR FIRE-EXTINGUISHING APPARATUS

Application filed September 13, 1928. Serial No. 305,687.

This invention relates to releasing mechanism for fire extinguishing systems wherein an electrically operated element serves to actuate a member for tripping an element which 5 effects the releasing operation desired. A construction of the above character is shown and described in the patent to Derby No. 1,187,135, dated June 13, 1916, for release box, and the present invention embodies an im- 10 proved construction whereby the above mentioned releasing mechanism is rendered cap- 15 able of manual operation.

An object of this invention is to provide a releasing mechanism which is capable of being operated either electrically or manually, 15 the construction being such that the elements constituting one operating mechanism do not interfere with the operation of the elements constituting the other form of operating 20 mechanism.

As a further feature, the mechanism is provided with a resetting mechanism which greatly facilitates this operation, partic- 25 ularly when done by inexperienced hands.

Further objects will appear as the invention is described more fully in connection with the accompanying drawings wherein:

Figure 1 is a view in side elevation, partly broken away and in section, showing a preferred form of the invention.

Figure 2 is a view in elevation, taken from the left in Figure 1, and showing the manual operating mechanism.

Referring to the above drawings, *a* indicates a housing provided with apertured lugs *a'* for securing the mechanism to a support. A lever *b* is pivoted at *b'* to the outside of the housing and is maintained in the position shown in Figure 1 by means of a 35 catch *b''* which engages a trigger arm *c'* upon pivoted lever *c*. Movement of lever *c* is prevented by the engagement of tooth *d'* with the end thereof. Tooth *d'* is formed on pivoted lever *d* and a spring *d''*, connected be- 40 tween the lever and a pivoted latch *e*, normally tends to move the tooth out of engagement with the end of the lever *c*. This movement is prevented by latch *e* which engages the upper extremity of the lever *d*. An elec- 45 tron magnet *f* is mounted on the housing above

the latch *e* and, when energized, serves to release the latch and permit spring *d''* to move the lever *d* to release the lever *c* which, in turn, releases lever *b*, thus permitting the fire extinguishing mechanism to be operated. An 55 aperture *a''* is formed in one face of the housing *a* and bracket *g* is mounted over the aperture to provide a bearing for a lever *h*. This lever is formed with an arm *h'* which extends upwardly into a second bracket *i* 60 which carries a cable *j*. The cable *j* may be of any desired length and has secured at the other end thereof a handle *j'* which is manually operated. If desired, a protective tube *i'* is mounted on the bracket to enclose the cable *j*, as shown in Figure 1. The lever *h* is held normally in the position shown in Figure 1 by spring *h''* and the force of this spring must be overcome when the device is to be manually operated. A pull on the handle *j'* is trans- 65 mitted through cable *j* and arm *h'* to lever *h* which overcomes the force of the spring *h''* and lifts the latch *e* upwardly. This disengages the lever *d*, described above, and permits the mechanism to be operated. 70

To effect the resetting of the mechanism, a plunger *k* is mounted in the housing *a*. This plunger is held in a retracted position by spring *k'* and may be pushed in manually to force lever *c* into operative engagement with levers *d* and *b*. After the lever *b* is moved to the position shown in Figure 1, plunger *k* is pushed inwardly to cause the lever *c* to engage the levers *b* and *d*, thus resetting the mechanism. 75

It will be seen that the electrical release may be effected in the usual manner as described in the above mentioned patent without interfering with the manual releasing mechanism in the slightest. If it should be 80 desirable to release the mechanism manually, the cable *j* is pulled, as described above, and the operation is accomplished.

It will be apparent that slight changes may be made in the design and arrangement 85 of the foregoing elements without departing from the scope of the invention as defined in the appended claims.

I claim as my invention:

1. A device of the character described com-

prising a housing, a movable member normally urged to a releasing position, a latch normally preventing such movement, electromagnetic means for disengaging the latch from the movable member, a pivoted lever, an arm on the lever for engaging the latch, and manual means to move the lever to disengage the latch.

2. A device of the character described comprising a housing, a movable member normally urged to a releasing position, a latch normally preventing such movement, electromagnetic means for disengaging the latch from the movable member, a lever, means to pivot the lever on the housing, an arm on the lever for engaging the latch, and manual means to move the lever to disengage the latch.

3. A device of the character described comprising a housing, a movable member normally urged to a releasing position, a latch normally preventing such movement, electromagnetic means for disengaging the latch from the movable member, an aperture in the housing, a lever, a bracket on the exterior of the housing for pivoting the lever thereto, an arm on the lever extending through the aperture and engaging the latch, means to urge the arm away from the latch normally, and manually operated means for moving the lever to disengage the latch.

4. A device of the character described comprising a housing, a movable member normally urged to a releasing position, a latch normally preventing such movement, electromagnetic means for disengaging the latch from the movable member, an aperture in the housing, a lever, a bracket on the exterior of the housing for pivoting the lever thereto, an arm on the lever extending through the aperture and engaging the latch, means to urge the arm away from the latch normally, a second bracket on the exterior of the housing, and manually operated means mounted on the second bracket and engaging the lever to move the arm to release the latch.

This specification signed this 29th day of August A. D. 1928.

WALTER H. FREYGANG.
